UNITED STATES PATENT OFFICE.

CECIL W. BARTO, OF PORT ANGELES, WASHINGTON.

FLOOR CLAMP.

Application filed June 2, 1925. Serial No. 34,404.

To all whom it may concern:

Be it known that I, CECIL W. BARTO, a citizen of the United States, residing at Port Angeles, in the county of Clallam and State 5 of Washington, have invented certain new and useful Improvements in Floor Clamps, of which the following is a specification.

This invention relates to a floor clamp, and has for its object to provide, in a manner as hereinafter set forth, a foot operated device of such class, with means for forcing flooring boards in closely abutting relation and for holding them in such position while they are being secured in place without 10 breaking or otherwise damaging the boards and further forming a very close seam between the boards.

Further objects of the invention are to provide, in a manner as hereinafter set forth, 20 a floor clamp for the purpose referred to, which is simple in its construction, strong, durable, compact, light in weight, conveniently positioned and anchored, thoroughly efficient in its use, and inexpensive to manufacture.

With the foregoing and other objects in view, the invention consists of the novel construction, combination and arrangement of parts, as hereinafter more specifically described and illustrated in the accompanying drawings, wherein is shown an embodiment 30 of the invention, but it is to be understood that changes, variations and modifications can be resorted to which come within the scope of the claims hereunto appended.

In the drawings wherein like reference characters denote corresponding parts throughout the several views:—

Figure 1 is a longitudinal sectional view 40 of a floor clamp, in accordance with this invention, and showing the adaptation thereof with respect to a floor formed from boards of the tongue and groove type.

Figure 2 is a sectional plan of the device 45 arranged in operative position.

Figure 3 is an inverted plan, partly in section.

Figure 4 is a section on line 4—4, Figure 1.

Figure 5 is a side elevation of the device.

Referring to the drawings in detail, 50 1 denotes a subfloor upon which is laid the floor 2, the latter being formed from boards 3 of the tongue and groove type.

A floor clamp, in accordance with this invention, comprises a rectangular base plate 4 of the desired length and width, and hav-

ing its lower face provided throughout with spaced anchoring barbs 5, adapted to enter the joist 1 so as to anchor the clamp forwardly of and in spaced relation with respect to the boards 3, which have been arranged to provide a portion of the floor 2.

Extending from one end of the base plate 4 is a guide tongue 6 of substantial length, thickness and width, and which is disposed centrally with respect to said end, and slidably mounted thereon is a square clamping member 7 having its working edge formed with a groove 8 for the reception of the tongue 9 of a board 3. The clamping member 7 is provided with an opening 10, into which extends the guide tongue 6.

Connected to the base plate 4 and inclining towards the clamping member 7 is a channel-shaped standard formed of a pair of spaced side members 11, 12, and a front member 13 which terminates at a point below the upper ends of the side members 11 and 12. Connected to the base plate 4 and spaced from the channel-shaped standard is a pair of opposed, spaced, vertical supports 14, 15, which incline towards the clamping member 7 and are of less height than the side members 11, 12 of the channel-shaped standard. The members 14, 15 are connected together by a brace piece 15'. Extending into the upper end of the channel-shaped standard and between the upper ends of the supports 14, 15, is a crosshead 16 of arcuate contour. One end of the crosshead 16 is bifurcated, as at 17, and its other end bifurcated, as at 18. The bifurcated end 17 of the crosshead 16 is arranged in the upper end of the channel-shaped standard and is connected therewith by a bolt 19, provided with a cotter pin 20. The bifurcated end 18 of the crosshead 16 is positioned between the upper ends of the supports 14, 15 and is connected therewith by a bolt 21, provided with a cotter pin 22.

The channel-shaped standard, supports 14, 15 and crosshead 16 provide an inclined, inverted yoke-shaped element constituting a support for the shifting mechanism for the clamping member 7, and further provide a handle for conveniently positioning the device when desired. The bolt 19 forms a pivot for a bell crank lever to be presently referred to, and the bolt 21 forms a pivot for a tread lever to be presently referred to.

The bell crank lever is indicated by the reference character 23 and extends into the

bifurcated end 17 of the cross-head 16 and projects towards the supports 14 and 15, and is pivoted on the bolt 19. The bell crank lever 23 is formed with an upper arm 5 24 and a lower arm 25, and with the latter of greater length than the former. The arm 25, when the bell crank lever is in normal position, extends in close proximity to the base plate 4.

- 10 Extending through the bifurcated end 18 of the cross-head 16 is a foot operated lever 26, pivoted intermediate its ends on the bolt 21, and having its outer end provided with a foot tread 27 and its inner end bifurcated, as at 28. Extending into the bifurcated end 28 of the lever 26 is the arm 24 of the bell crank 23, and the said bifurcated end 28 and arm 24 are pivotally connected together by a bolt 29 provided with a cotter pin 30.
- 15 Connected to the clamping member 7 and extending between the supports 14 and 15 is a shifting bar 31 for the clamping member 7. The bar 31 projects inwardly from the supports 14 and 15 and has a bifurcated inner end 32, into which extends the lower end of the arm 25 of the bell crank 23. The bifurcated end 32 of the bar 31 and the lower end of the arm 25 of the bell crank lever 23 are pivotally connected by a bolt 33, provided with a cotter pin 34.

The bell crank lever 23 is spring controlled, and the controlling spring therefor is indicated at 35. One end of the spring 35 is connected to the front member 13, as at 36, and its other end is connected to the arm 25, as at 37. The spring 35 normally maintains the bell crank 23, lever 26 and bar 31 in the dotted line position, as indicated in Figure 1. The full line position of 40 said elements, as shown in Figure 1, is when the foot lever 26 has been depressed by the foot 38 for the purpose of having the clamping member 7 force a floor board 3 in abutting relation with respect to an adjacent 45 floor board. When the lever 26 is relieved from pressure, the spring 35 restores the bell crank lever 23, lever 26 and bar 31 to the dotted line position shown in Figure 1.

When using the device, it is placed adjacent to a floor board, which is to be forced in abutting relation with respect to a secured floor board, and by pressing downwardly on the foot lever 26 the floor board 55 is forced to abutting relation to a secured floor board, as illustrated in Figure 1.

When the foot lever 26 is depressed, the bell crank lever 23 is shifted on its pivot, whereby the arm 24 thereof is moved upwardly and the arm 25 forwardly, under such conditions forcing the bar 31 in a direction to 60 shift the clamping member 7 to the position shown in Figure 1.

What I claim is:—

1. A floor clamp comprising a base plate, an inverted yoke-shaped element carried thereby, a clamping member, a shifting bar therefor, and operating means for said bar, said means including a bell crank pivotally connected to said element and a shifting lever for the bell crank pivotally connected 65 to said element and to one of the arms of said lever.

2. A floor clamp comprising a base plate, an inverted yoke-shaped element carried thereby, a clamping member, a shifting bar 75 therefor, operating means for said bar, said means including a bell crank pivotally connected to said element and a shifting lever for the bell crank pivotally connected to said element and to one of the arms of said 80 lever, and a guide carried by said base plate for said clamping member.

3. A floor clamp comprising a base plate, an inverted yoke-shaped element carried thereby, a clamping member, a shifting bar 85 therefor, operating means for said bar, said means including a bell crank pivotally connected to said element and a shifting lever for the bell crank pivotally connected to said element and to one of the arms of said 90 lever, and a controlling spring for said bell crank, said spring being connected to said element and to one of the arms of the bell crank.

4. A floor clamp comprising a base plate, 95 an inverted yoke-shaped element carried thereby, a clamping member, a shifting bar therefor, operating means for said bar, said means including a bell crank pivotally connected to said element and a shifting lever 100 for the bell crank pivotally connected to said element and to one of the arms of said lever, a guide carried by said base plate for said clamping member, and a controlling spring for said bell crank, said spring being 105 connected to said element and to one of the arms of the bell crank.

In testimony whereof, I affix my signature hereto.

CECIL W. BARTO.
